Patented Feb. 11, 1919

Fig. 1.

UNITED STATES PATENT OFFICE.

OLOF D. M. GUTH, OF EAST ORANGE, NEW JERSEY, ASSIGNEE TO WESTERN ELECTRIC COMPANY, INCORPORATED, OF NEW YORK, N. Y., A CORPORATION OF NEW YORK.

IMPULSE-TRANSMITTER.

1,284,095.

Specification of Letters Patent. Patented Feb. 11, 1919.

Application filed July 14, 1917. Serial No. 128,601.

To all whom it may concern:

Be it known that I, OLOF D. M. GUTH, a citizen of the United States, residing at East Orange, in the county of Essex and State of New Jersey, have invented certain new and useful Improvements in Impulse Transmitters, of which the following is a full, clear, concise, and exact description.

This invention relates to impulse transmitters of the type which are used in connection with telephone systems employing directly controlled automatic switches, whereby a set of impulses comprising one or more series of impulses may be transmitted for effecting the operation of such automatic switches.

Ordinarily, impulse transmitters by which automatic switches of this character are controlled, must be operated slowly so that the transmission of the impulses will properly control the switches. This means that the calling operation will tend to delay the work of the person making the call and will also require too much time and effort of such person on account of the more or less deliberate manner in which the manual manipulation of the impulse transmitter must be performed.

Generally stated, therefore, the object of this invention is to provide an improved and highly efficient impulse transmitter which is simple to operate and which is capable of being manipulated as fast as the operator desires without effecting the speed at which the impulses are transmitted.

In accordance with this object of the invention, an impulse transmitter is provided in which a single set of keys is sufficient for calling a number having a plurality of digits, and mechanism is provided whereby the impulse transmitting mechanism is automatically released after a predetermined number of keys have been depressed to automatically transmit series of impulses in accordance with the depressed keys. For example, if the transmitter is designed for a four digit number, the impulse transmitting mechanism is released when the fourth key, which corresponds to the units digit of the number, is depressed. The impulse transmitting mechanism sends out first, a series of impulses in accordance with the first key depressed, which corresponds to the thousands digit; second, a series of impulses in

accordance with the second key depressed, which corresponds to the hundreds digit, etc., until the four series of impulses corresponding to the four keys depressed have all been transmitted. The mechanism of the transmitter is also arranged so that during the setting up of the number before the impulse transmitting mechanism is released, any key may be depressed more than once, as is the case when two or more digits of the called number are the same.

Other objects and features of this invention will appear from the following description and claims. In the drawing; Figure 1 is a perspective view of the transmitter with part of the case broken away to show the operating mechanism; and Fig. 2 is a section looking down on the line 2--2 of Fig. 1.

Referring to the drawing, 1 designates a case in which the impulse transmitting mechanism of the transmitter is inclosed. An upright post 2 is mounted in the center of the base of this case 1. A notched disk 3 of conducting material is insulatedly secured to the bottom of the post 2, this disk 3 being also insulated from the bottom of the case 1. A flat circular ring 4 of conducting material surrounds the outer edge of the disk 3. This ring 4 is insulated from both the disk 3 and the bottom of the case 1. A sleeve 5 is rotatably mounted on the post 2 and secured to this sleeve is an arm 6 upon which three brushes 92, 7 and 8 are mounted. The brushes 92 and 7 engage the disk 3 and the brush 8 engages the circular ring 4, so that as the arm 6 is rotated a circuit is continuously completed between brush 8 and ring 4, and between brush 92 and disk 3, but the circuit between brush 7 and disk 3 is interrupted by the brush engaging a notch of the disk. The arm 6 has an upward projection 9 to which is fastened a yoke 10 carrying a rotatable spindle 11. A cam 12 is fastened to one end of the spindle and a roller 13 of insulating material cooperates with the surface of the cam to control the springs 14 and 15, which are insulatedly mounted on the projection 9. The spring 15 is connected to brushes 7 and 8 by conductor 94, and spring 14 is connected to brush 92 by a conductor 93. The cam 12 is provided with eight notches of which alternate ones are of sufficient depth to allow the springs 15 and 16 to separate when the roller 13 moves into them. The

other four notches are not of sufficient depth to allow these springs to separate when the roller moves into them, but instead the roller serves to hold the spindle 11 in its actuated position. The cam 12 is provided with four pins 16 extending inward toward the post 2 and parallel to the spindle 11. Four spirally arranged pins 17 extend radially from the spindle 11.

16 A gear 18 is fastened to the sleeve 5 and meshes with a gear 19 fastened to a sleeve 20 which is rotatably mounted on a post 21 extending downward from the end of a yoke 28. The other end of the yoke 28 is fastened 15 to the projection 29, which in turn is fastened by means of the sleeve 96 to the arm 42, which is fastened to the side of the case 1. A gear 22 is also fastened to the sleeve 20 and it meshes with gear 23, fastened to a 20 sleeve 24 which is rotatably mounted on the post 2. A toothed wheel 25 is also fastened to the sleeve 24 and a holding dog 26 normally engages the wheel to prevent it from being rotated. The dog 26 is pivotally 25 mounted to a projection 27 of the yoke 28. An arm 31, integral with projection 29 is also supported by the arm 42 and is so arranged that as the arm 6 is rotated and passes the stationary arm 31, the end of this 30 arm 31 engages a pin 16 on the cam 12 to rotate the spindle 11 one eighth of a turn to position one of the pins 17 so that it projects directly upward.

A sleeve 30 is rotatably mounted on the 35 post 2 and has fastened thereto two arms 32 and 33 each of which is provided with a pin for engaging the holding dog 26. As shown in the drawing, if the sleeve 30 is rotated in a clockwise direction a quarter of 40 a revolution, the pin secured to arm 33 will engage the holding dog 26 and withdraw it from the toothed wheel 25. The wheel is then rotated in a counter-clockwise direction by a spiral spring 37, one end of which 45 is fastened to the projection 29 and the other end to the sleeve 30. The sleeve 30 is prevented from rotating without the toothed wheel 25 in counter-clockwise direction by a pawl 35 which is pivotally mounted on the arm 33 and which is spring-pressed into 50 engagement with the toothed wheel. When the sleeve 30 reaches its normal position the pin secured to the arm 32 engages the holding dog 26 and moves it into engagement with the toothed wheel, thereby stopping further 55 rotation of the sleeve 30 and the toothed wheel 25 in a counter-clockwise direction. A spring 34 is fastened to the dog 26 and the yoke 28 in such a manner that when the dog 60 26 is in engagement with the toothed wheel 25, the line of action of the spring is such that it tends to hold the dog in engagement with the wheel, and when the dog is out of engagement with the toothed wheel, the line 65 of action of the spring is such that it tends

to hold the dog out of engagement with the wheel.

A flat disk 38 is rotatably mounted on the sleeve 96 and it has mounted thereon a circular ratchet wheel 39. A lever 41 is pivotally mounted to the arm 42 fastened to the side of case 1. The lever carries at one end a pawl 40, which is spring-pressed into engagement with the circular ratchet wheel 39 to rotate the wheel in a clockwise direction. 70 Extending radially from the edge of this disk, there are ten sets of flat flexible springs, each set comprising four springs 43. Between each set of springs, a space equal to the distance between two springs is left for 80 a purpose hereinafter described. As shown in the drawing, the first spring of each set has a lug 70 projecting downward near its outer end. The second spring of each set has a lug 71 projecting downward, but not so 85 near the end as the lugs 70. The third and fourth springs have the lugs 72 and 73 respectively, projecting downward still nearer the center of the device. The lugs are so arranged that when they are pressed downward they will be in the path of a pin 17 on the spindle 11, and by engaging one of the pins rotate the spindle one eighth of a turn. This operation will be hereinafter 90 more fully described.

95 A circular bracket 44 is fastened to the inner side of the case 1 and the springs 43 are arranged to normally move just above this bracket. In the normal position of the device the first spring of each set is directly 100 above a notch in this bracket and directly above each of these springs is a key 63 which extends upward through the top of the case 1. Each of these keys 63 is normally held out of engagement with the flat springs 43 105 by a helical spring 64, one end of which is fastened to the key 63 and the other end to a Z-shaped member which is fastened to the bracket 44 and which also serves as a guide for the key 63 to move it directly downward 110 when it is depressed. The depressing of one of these keys moves the end of the flat spring, which is directly under it, downward so that when the disk 38 is rotated, the end of this spring slips underneath the bracket 115 44 and is held in this position until it reaches the next notch in the bracket, at which time it moves upward into its normal position above the bracket.

A flat disk 50 is loosely mounted on the 120 post 2. It is normally held against a collar 75 on the post 2 by a spring 52, one end of which is fastened to the disk 50 and the other end to a collar 76 on the post 2. The disk 50 is supported near its outer edge by rods 60 125 which are connected at one end to the disk by a ball and socket joint 61 and to bracket 44 at their other end by a ball and socket joint 62. These rods are arranged so that when the disk 50 is moved downward, the 130

rods cause the disk to rotate clockwise. The disk 50 is provided with slots 53 through which keys 63 project, and these slots are shaped so that they allow a rotation of the disk 50 relative to the keys 63. Each key 63 carries a roller 65 which engages the upper surface of the disk 50 and serves to press the disk downward when its corresponding key is depressed.

10 The disk 50 has a projection 77 which carries a roller 54. This roller engages a guide member 66 fastened to a sleeve 55 which is loosely mounted on the post 2. The sleeve 55 carries an arm 56 which is arranged to engage the lever 41 and thereby rotate the disk 38. The sleeve 55 is also provided with ratchet teeth which are arranged to engage ratchet teeth on sleeve 30, but these two sleeves are normally held out of engagement by a spring 81, one end of which is fastened to the projection 77 of disk 50, and the other end of which is fastened to the guide member 66 of sleeve 55. The sleeve 55 is normally held against the collar 76 and 25 the guide member 66 against roller 54 by the spring 81.

The operation of the sender is as follows, it being assumed that the sender is normally in the condition shown in the drawing and 30 that the number to be called is 1123. The person operating the sender will press the key No. 1 twice; then the keys No. 2 and No. 3, respectively. The first depression of key No. 1 moves the spring 43 carrying lug 35 70, which is directly underneath the key, downward. The roller 65 of this key moves the disk 50 down against the compression of spring 52, and also rotates the disk 50. This combined downward movement and 40 rotation of the disk is transmitted to the sleeve 55 by the roller 54 so that the sleeve 55 moves down into engagement with sleeve 30. The rotation of sleeve 55 produced by this depression of the key is sufficient to 45 bring the arm 56 into engagement with lever 41 to rotate the disk 38 so that the next spring of each set of springs is positioned above the notches in the bracket 44, and also to move the depressed spring 43 underneath the bracket 44, so that it is held in 50 its depressed condition until the sender reaches its next normal position. The sleeve 30 is rotated a distance equal to one quarter the distance between arms 33 and 32. This 55 rotation of sleeve 30 is against the tension of spring 37 and the sleeve is held in its operated position by pawl 35 engaging a tooth of wheel 25 which is at this time prevented from rotating by holding dog 26.

60 The second depression of key No. 1 operates the mechanism the same as before except in this case the spring 43 of the first set carrying the lug 71 is depressed and moved underneath the bracket 44. The depression of keys No. 2 and No. 3 also oper-

ates the mechanism in the same way as above described, except that the spring 43 carrying lug 72 of the set corresponding to key No. 2 and the spring 43 carrying lug 73 of the set corresponding to key No. 3 are depressed 70 respectively and moved underneath the bracket 44.

When the arm 33 reaches the end of its rotation in response to the depression of the fourth key, the pin on this arm engages the 75 holding dog 26 and withdraws it from engagement with the toothed wheel 25. The sleeve 30 and the toothed wheel are now rotated in a counter-clockwise direction by spring 37. The rotation of the toothed 80 wheel is transmitted by sleeve 24, gears 23, 22, 19 and 18 to the arm 6. This gear ratio is such that the arm 6 makes four complete revolutions while the sleeve 30 is returning to its normal position. As soon as the arm 85 6 leaves its normal position, the upper pin 16 on the cam 12 hits the arm 31 and rotates the spindle one eighth of a turn so that the right-hand pin 17 extends directly upward. The roller 13 is also moved into a deep 90 notch of cam 12 so that the normally closed contact springs 14 and 15 are opened, thereby transferring the current that normally passes therethrough to the control of brushes 7 and 8, this new circuit being 95 traceable from line conductor 90, disk 3, brushes 7 and 8, conducting ring 4 to line conductor 91. As soon as the brush 7 engages a notch of the disk 3 the circuit through the line conductors 90 and 91 is 100 opened for a short interval but it is again closed as soon as the brush 7 again engages the conducting portion of the disk. When the arm 6 has rotated far enough so that one 105 interruption has been produced in the line circuit, the lug 70 of the first set of springs engages the upright pin 17 and rotates the spindle 14 an eighth of a turn. The roller 13 is now in a narrow notch so that the contact springs 14 and 15 are closed, thereby 110 closing a shunt around brushes 7 and 8, thereby preventing any more interruptions in the circuit between conductors 90 and 91 during the remainder of the revolution of arm 6. This shunt circuit may be traced 115 from line conductor 90, disk 3, brush 92, conductor 93, contact springs 14 and 15, conductor 94, brush 8, ring 4, to line conductor 91. As soon as the arm 6 starts on its second revolution another pin 16 which was 120 positioned by lug 70 engaging the pin 17, engages the arm 31 to rotate the spindle another eighth of a turn and position the pin 17 which is second from the right-hand end of spindle 11. The shunt circuit of 125 brushes 7 and 8 is also opened at this time by roller 13 engaging a deep notch in the cam 12, so that impulses are again transmitted over the line conductors 90 and 91 by the rotation of the arm 6. After one impulse 130

has been transmitted the lug 71 of the first set of springs engages the upwardly projecting pin 17 to rotate the spindle another eighth of a turn and thereby shunt the brushes 7 and 8 in the same way as above described to prevent any more impulses being transmitted during the remainder of the revolution.

The arm 6 continues to rotate, and under the control of lug 72 of the second set of springs, and lug 73 of the third set of springs, two impulses and three impulses are transmitted respectively.

When the sleeve 30 reaches its normal position, the pin on arm 32 moves the pawl 26 into engagement with the toothed wheel 25, thereby stopping the arm 6 in its normal position. The line circuit is maintained in this position through the springs 14 and 15 because the arm 6 is stopped from rotating before the pin 16 engages the arm 31.

Also when the sleeve 30 reaches its normal position an arm 80, which is carried by the sleeve, engages the lever 41 and rotates the disk 38 so as to position the first spring of each set of springs directly over the notches in the bracket. It will be remembered that when the fourth key was depressed the disk 38 was rotated in the same manner as before, but, due to the double space between the sets of springs, the depressed springs 43 were still held underneath the bracket 44.

The device is now in condition for transmitting another set of impulses. The springs 43, which were depressed by the second, third and fourth depressed keys respectively, are still held under bracket 44, but as soon as the sender is used again and disk 38 rotated by each depression of a key, these depressed springs will be released in the order named.

What is claimed is:

1. In a calling device, a set of keys, an impulse transmitting mechanism, and means automatically operated by the depression of any one of said keys after a predetermined number of keys have been depressed for operating said mechanism.
2. In a calling device, a set of keys, an impulse transmitting mechanism normally prevented from operating, and means operated by the depression of said keys to automatically release said mechanism after a

predetermined number of keys have been 65 depressed.

3. In a calling device, an impulse transmitting mechanism normally prevented from operating, a set of keys for adjusting said mechanism, and means for automatically releasing said mechanism dependent on the actuation of a predetermined number of keys to allow said mechanism to transmit series of impulses corresponding to the keys previously depressed.

4. In a calling device, an impulse transmitting mechanism, a set of keys, means adjusted by each depression of a key for predetermined the number of impulses to be transmitted by said mechanism, means for 70 preventing said mechanism from operating during said adjusting, and means for automatically releasing said mechanism dependent on the actuation of a predetermined number of keys to allow said mechanism to 75 transmit series of impulses corresponding to the keys previously depressed.

5. In a calling device, an impulse transmitting mechanism, a source of energy for operating said mechanism, holding means 80 for preventing said mechanism from being operated, a set of keys, means adjusted by each depression of a key for predetermined the number of impulses to be transmitted by said mechanism, means operated by each depression of a key for increasing the energy of said source, means for automatically withdrawing said holding means after a predetermined number of keys have been depressed to allow said mechanism to be operated by said source of energy to transmit series of impulses corresponding to the keys previously depressed, and means for restoring said holding means when all of said series of impulses have been transmitted.

6. In a calling device, a set of keys, impulse sending mechanism, means for causing said mechanism to operate dependent on the actuation of a predetermined number of keys, means adjusted by the depression of 100 the keys for controlling the sending mechanism in its operation, and means actuated at the completion of the impulse sending operation for placing said adjustable means in condition for subsequent adjustment.

In witness whereof I hereunto subscribe my name this 12th day of July A. D., 1917.

OLÖF D. M. GUTHÉ.
